(No Model.)

H. W. RANSOM.

FIFTH WHEEL.

No. 392,825.

Patented Nov. 13, 1888.

Fig. 1.

Fig. 2.

UNITED STATES PATENT OFFICE.

HIRAM W. RANSOM, OF CINCINNATI, OHIO.

FIFTH-WHEEL.

SPECIFICATION forming part of Letters Patent No. 392,825, dated November 13, 1888.

Application filed October 29, 1887. Serial No. 253,692. (No model.)

To all whom it may concern:

Be it known that I, HIRAM W. RANSOM, a resident of the city of Cincinnati, in the county of Hamilton and State of Ohio, have invented 5 certain new and useful Improvements in Fifth-Wheels, of which the following is a specification.

The several features of my invention and the advantages arising from their use will be apparent from the following description.

In the accompanying drawings, forming part of this specification, Figure 1 is a front elevation of a portion of an axle and head-block provided with my improved fifth-wheel. Fig. 2 15 is a top view of the same; and Fig. 3 is a section taken at the line $x-x$, Fig. 1. Fig. 4 is a central vertical section of the axis.

The bar B is fitted to the under side of the head-block A, and is secured in position by 20 any desirable means, preferably the clips C, whose ends pass through the lugs b, projecting from the bar B, and are bolted thereunder. The lug B' projects rearwardly from the bar B, and is provided with a central opening, 25 through which the king-bolt passes. Bars D and E, similar to bar B, are secured to the upper and lower surfaces of the axle F, the means for securing them being preferably the clips G. The bars D and E are, like the bar 30 B, each provided with a rearwardly-projecting lug, (marked, respectively, in the drawings as D' and E'.) The lugs D' and E' each have an opening through which the king-bolt passes. The king-bolt H is attached to the rear face of 35 the head-block. It is provided with a projecting arm or offset, H', which throws it backward, thus bringing the axis of the fifth-wheel somewhat behind the axle and head-block.

The fifth-wheel proper consists of the upper 40 are, I, attached to the head-block, and is preferably made integral with the bar B, and the lower are, I', is preferably made in two parts, as illustrated, and is attached to the axle. The upper are, I, is provided with a downwardly-projecting flange, i, on its outer edge. The head-block is braced by both front and rear braces. The rear brace, J, is attached to the head-block in any desired manner, but preferably by being made integral with the bar B. 45 The brace J curves backwardly and downwardly and is bolted to the perch K. The

front brace, L, is attached to the anterior face of the head-block, and projects forward, then downward, then backward, and is attached to the under surface of the perch. This brace 55 partially surrounds the axle, and is sufficiently far from it to allow free play of the axle. The perch-brace M projects forwardly and upwardly and terminates under the lug D'. The king-bolt passes through an opening in the 60 end of the brace M. The brace M, by projecting only slightly upward and not reaching above the top of the axle, makes the draft more direct—a feature of importance in a drop-perch vehicle. Between the brace M and the 65 lug E' the king-bolt is preferably protected by a surrounding ferrule, N.

As shown in Fig. 3, the king-bolt H passes through the lugs B' D', brace M, ferrule N, lug E', and brace L, and there is preferably 70 screwed to the lower end a nut, h, although this last element is not necessary.

What I claim as new, and desire to secure by Letters Patent, is—

1. The combination of a head-block and axle 75 respectively provided with fifth-wheel arcs, lugs B', D', and E', projecting rearwardly from the head-block and axle, respectively, king-bolt attached to the rear face of the head-block and projecting rearwardly therefrom, anterior encircling brace, and posterior perch-brace M, substantially as and for the purposes specified.

2. The combination of a head-block and axle 80 respectively provided with fifth-wheel arcs, lugs B', D', and E', projecting rearwardly from 85 the head-block and axle, respectively, king-bolt attached to the rear face of the head-block and projecting rearwardly therefrom, anterior encircling brace, and posterior perch-brace M, projecting rearwardly from the king-bolt, and 90 brace J, projecting rearwardly and downwardly from the posterior portion of are I and attached to the perch, substantially as and for the purposes specified.

3. The combination of a head-block and axle 95 respectively provided with fifth-wheel arcs I and I', the upper arc being provided with the flange i, lugs B', D', and E', projecting rearwardly from the head-block and axle, respectively, king-bolt attached to the rear face of the 100 head-block and projecting rearwardly therefrom, anterior encircling brace, and posterior

perch-brace M, projecting rearwardly from the king-bolt, and brace J, projecting rearwardly and downwardly from the posterior portion of arc I and attached to the perch, substantially as and for the purposes specified.

4. The combination of fifth-wheel arc I, bar B, and brace J, made in one piece, the brace

J extending from the ends of the arc I downward and backward, substantially as and for the purposes specified.

HIRAM W. RANSOM.
